CONTROL UNIT FOR AN ANTENNA ROTATOR

Raymond Kaysen, Glenside, Pa., and Franklin Roosevelt Di Meo, Woodbury, N.J., assignors to RCA Corporation

Filed Feb. 5, 1973, Ser. No. 329,611

Term of patent 14 years

Int. Cl. D13—03

U.S. Cl. D26—13 R

Fig. 1.

Fig. 2.

Fig. 3.

Fig. 4.

Fig. 5.

Fig. 6.

FIG. 1 is a top plan view of a control unit for an antenna rotator, showing our design,

FIG. 2 is a first end elevation view thereof,

FIG. 3 is a second end elevation view thereof,

FIG. 4 is a right side elevation thereof,

FIG. 5 is a bottom view thereof,

FIG. 6 is a left side elevation thereof, and

FIG. 7 is a perspective view thereof.

I claim:

The ornamental design for a control unit for an antenna rotator, as shown.
